UNITED STATES PATENT OFFICE

STANLEY W. HAYES, OF RICHMOND, INDIANA, ASSIGNOR TO HAYES TRACK APPLIANCE COMPANY, OF RICHMOND, INDIANA, A CORPORATION OF INDIANA

SCOTCH BLOCK

Application filed September 30, 1931. Serial No. 566,045.

The invention is an improved and simplified scotch block or the like for use on railway tracks, and is primarily applicable to the type of scotch block disclosed in the 5 Whilt Patent No. 1,369,910 and in which parts of the block extend below the base of the rail into the plane of the ties to insure dissipation of the shock of car wheel impact to the ties and ballast. The scotch block of this 10 application also embodies certain aspects of the scotch blocks disclosed and claimed in Patent No. 1,801,917 issued to the present applicant April 21, 1931, and in his pending application filed October 18, 1930, Serial No. 15 489,524. The object of the invention is the provision of a light, strong and efficient scotch block capable of production at relatively low cost and having improved and readily applicable clamping means for maintaining it upright on the rail, and the invention consists in the subject matter of this nature illustrated and described herein and set forth in the appended claims defining its 20 scope.

Referring to the drawings:

Fig. 1 is a perspective view of one of the scotch blocks on the rail;

Fig. 2 a perspective on a larger scale showing the principal members of the scotch block ready for assembling;

Fig. 3 is a front sectional elevation on the line III—III of Fig. 4;

Fig. 4 is an enlarged detail plan indicating the mode of connection of the clamping members to the block;

Fig. 5 is an enlarged detail perspective of the left-hand clamping member;

Fig. 6 is an incomplete sectional front elevation showing the scotch block applied to a smaller rail than that shown in Figure 3.

Fig. 7 is a side elevation of a modification of the invention.

Fig. 8 is a plan corresponding to Fig. 7;

Fig. 9 is a front elevation, partly in section, of the modified block applied to a heavy rail;

Fig. 10 is a front elevation showing this block applied to a lighter rail;

Fig. 11 is an incomplete rear sectional ele-

vation on the line XI—XI, Fig. 7 showing details of the block of Fig. 10;

Fig. 12 is a perspective of the lefthand clamping member of Figs. 9 and 10;

Fig. 13 is a perspective of a scotch block 55 embodying a third modification of the invention;

Fig. 14 is a perspective of parts of this scotch block in readiness for assembling;

Fig. 15 is a detail perspective on a larger 60 scale illustrating the parts of the double clamping jaw before their assembling and welding together;

Fig. 16 is a perspective of the finished jaw; 65 and

Fig. 17 is a vertical sectional front view of this particular scotch block assembled on the rail.

Referring to Figs. 1 to 6, the block proper, marked 1, is an upright flat plate forming by 70 its front curved edge a contact surface 2 which will be termed the car wheel abutment. It may be economically produced by punching or cutting it out of a steel plate with the desired contour. This plate or block extends 75 up from the rail a distance of $16\frac{1}{16}$ ", or substantially to the level of the car wheel axis, so as to preclude overrunning of the block by the wheel. It is provided with rigid downward extensions at each side of the rail, reaching 80 to the plane of the ties, and through which it is adapted to transmit the shock or stress of car wheel impact to the tie and ballast. These extensions may conveniently be formed by passing one leg 3 of an inverted 85 U-shaped sheet steel tie-face-abutment member through the rear slot 4 in plate 1 and welding it thereto in symmetrical relation to the plane of the plate. The means for holding the block upright on the rail so that it 90 will be secure against displacement from accidental causes but may yet slide along the rail under the car wheel impact, may be variously constructed within the principle of this invention and in the form of Figs. 1 to 6 95 95 comprises clamp jaw supporting structure extending rigidly downward from the plate at each side of the railhead and conveniently constituted by the legs 5 of an inverted U-shaped plate member, which is most readily 100

secured to the plate 1 by inserting it through the forward slot 6, or notched lower edge of the plate 1 and welding it thereto in symmetrical relation to the plane of the plate. 5 Each leg, in the figures referred to, is braced and further connected to the plate by a gusset lug 7 which is welded in the corner which the leg 5 makes with the plate so that it serves as reinforcement to the leg, being welded to both 10 the leg and the plate as indicated in Fig. 4. The plane of the upper side of each of these gusset-lugs or corner pieces makes an acute angle with the plane of the abutment plate, as appears in Fig. 3. A floating clamping jaw 15 8 (Fig. 5) preferably formed of bent steel plate is adjustably mounted on the abutment structure just referred to, in rear of each leg 5 on which it is adapted to be adjusted and to which it is clamped after adjustment. Each 20 jaw is suspended from the gusset lug 7 by a supporting and adjusting bolt 9 introduced into and loosely fitting holes in the lug and in the bent-over top 10 of the clamping jaw, which is thus suspended directly from the 25 bolt head. By reason of the loose-fit of the bolt, the clamping jaw is permitted a certain lateral movement and by adjusting the bolt it can be raised or lowered on the leg 5. The head of the bolt is prevented from turning by 30 its proximity to the adjacent side of the clamping jaw, but its nut 11 is easily accessible on the top side of the lug for manipulation. It may be noted here that the longitudinal axis of the bolt lies in the plane extending lengthwise of the rail and normal to the face of the gusset lug or corner piece 7. This plane α crosses from below upward and inward the plane γ extending lengthwise of the rail and containing the major axis of the 35 40 adjacent leg. Adjustment of the bolt endwise thus provides a cross draw of the clamping jaw inward and upward toward the rail. Each leg 5 has a slot 12 extending lengthwise thereof and symmetrically related to the longitudinal axis of the leg, and each clamping 45 50 jaw 8 has a corresponding slot 13 whose longitudinal axis makes an angle with that of the other slot. A cross bolt 14 occupying these slots serves to secure the jaw in its adjusted position as presently explained. This arrangement permits adjustment to rails of any height within the contemplated range. Each said jaw 8 is shaped to engage the rail, and preferably at three points of contact 55 therewith marked 16, 17 and 18 respectively and being at the side of the rail head (16) under the rail head (17) and on the edge of the base flange (18). The inner edge of the jaw is shaped accordingly, seats 16 and 18 being 60 preferably in a common plane.

In this as in the other forms of the invention the operation of applying the block to the rail involves a preliminary clamping to a moderate seating against the rail head by 65 the adjustment in Figs. 1 to 6, of the bolts 9,

which ordinarily swing the lower ends of the clamp jaws somewhat outward away from the rail. The lower ends of the jaws are then forced inward against the rail flanges symmetrically, the block being thereby centered 70 on the rail; the parts are then secured in this position by tightening the nuts 15 on the cross bolts. By reason of the angularity of the jaw slots, pressing the cross-bolts downwards will serve to close the jaws on the rail. Washers may of course be supplied, though not shown. With this construction in which both clamping jaws extend below the base of the rail it is possible to clamp the scotch block 75 with sufficient security to the rail to maintain 80 it safely erect at all times while leaving it free to yield or slide thereon when a car wheel strikes it so hard as to drive it, and its tie rearwardly, there being no danger of excess clamping friction such as might cause the 85 block to break instead of yielding or sliding and no tendency to cramping action by the clamping jaws which action is prevented by the legs 5 which, on any movement by car 90 wheel impact carry the clamping jaws with them, i. e. push their rail seats rearwardly so that there is no binding. This structure, in 95 which each clamping jaw has a position of double tangency to the adjacent side of the rail, i. e. at 16 and 18, affords a maximum of 100 lateral rigidity for the block because of this fact alone. To prevent upward movement or jumping of the block off the rail, on car wheel impact, the jaws should, however, extend under the rail head or rail base, or separate 105 means for that purpose should be provided. It will be seen that the construction described provides in all a seven point clamping contact with the rail, i. e. the seat of the plate 1 110 on the rail and the six seats arranged symmetrically in sets of three each at each side of the rail. This arrangement, and in particular the extension of the clamping jaws below the base of the rail, is preferred and 115 has advantages not possessed by structures in which clamping jaws do not extend down far enough to seat on the rail flange edge. Shorter jaws however may be employed within the invention, though not affording these 120 advantages.

Referring to the modified form shown in Figs. 7 to 12, this is a light low cost structure of the tie-pusher type, in which the tie abutment members occupy the same position on the block proper as the clamp means, thus simplifying the structure. In this scotch block the plate or block 1, which seats on the rail tread, has welded thereto at each side thereof a little above the rail a horizontal shelf-like plate 19, both of these plates or shelves being located in the same horizontal plane and each having its rear end down-turned as at 20 so that the space between such ends forms a notch or crotch to embrace the rail and provide centering means of a 125 130

sort for the rear of the abutment block. The sloping leg members 21, which are welded symmetrically to the opposite sides of the abutment block are reinforced by the plates or shelves 19, being seated in and welded to notches cut in the latter. These leg members 21 are inwardly facing channels having their flanges bevelled at their upper ends, according to the angle of their slope, and extend downward and outward into the plane of the ties so that the rear flange 22 of each provides an extended tie-face abutment surface. The shelves 19 to which the legs 21 are welded serve to brace and further strengthen the structure against stress of car wheel impact. In this, as in the construction illustrated in Figs. 1 to 6 and already described lever action clamping means are provided, in the form of a pair of clamping jaws 23, one at each side of the rail and housed in the respective channeled legs 21, to which they conform. These jaws are in the nature of plates bearing and adapted to be clamped flatwise to each side of the rail in planes angular thereto and so to have a double contact therewith, thus providing longitudinally extended bearings or seats along the head and base of the rail at both sides of it and constituting a V-shaped structure with movable sides. Each leg includes a clamping jaw 23, which is however adjustably supported from the opposite leg. This is accomplished by the adjustable cross-clamp bolts 24 mounted in the respective legs in adjacent transverse vertical planes and having hooked lower ends 25 from which are suspended the jaws 23, each of which has in its upper end a hole 26 through which the bolt passes. Accidental disengagement may be guarded against by slightly upsetting the ends 25, as indicated at 27. Each bolt passes through an opening 28 in the abutment plate upward and outward through a hole in the leg which supports it and through the angle bracket 29 welded to the outside of the leg 21. The adjusting nut 30 finds a square bearing on this bracket. The structure is duplicated at each side of the block, save for the reversal of the respective clamping jaws, the staggering of the supporting and adjusting bolts and related structure and the omission respectively of the front or the rear top corner of one jaw to leave room for the cross bolt connection to the other. The support given to the plate jaws by the flanges of the channeled legs keeps them from cramping on the rail head when the block is moved by a car wheel and thereby insures that the device will slide on the rail to such extent as permitted by the adjacent tie. Each of the clamping jaws has means to engage the underside of the rail head, these being provided by a lug 32 (Fig. 12) which is appropriately shaped for the purpose. Also the jaws seat at 31 on the

rail head and extend below the base of the rail sufficiently to be applicable to rails of different heights within the range to which the block is adapted, so as to provide a seat surface 33 adapted to be clamped against the outside edge of the rail base by the action of screws 34 in the leg structure.

In this, as in the structure already described, the clamping jaws are first adjusted to a moderate clamping contact with the rail head, the screw 34 being backed off at this time sufficiently to allow this action to take place. This preliminary clamping is done by the use of nuts 30 to move the respective bolts 24 endwise and draw the opposite clamping jaw plates crosswise inward and upward against the rail head. The final centering and clamping of the block is then effected by screwing the screws 34 inward thereby forcing the jaws against the rail, after which nuts 30 may be further tightened if thought desirable. This operation can be quickly performed.

Referring to Figures 13 to 17 inclusive, which illustrate a third form, the block 1 is provided with the car wheel abutment 2, as in the other figures, and with the rear inverted-U-shaped tie-face-abutment member 3 passed through slot 4 in the abutment plate and welded thereto. In the lower edge of the block 1 near its front end is a notch 36 in which seats and is welded the bridge of a bifurcated bracket symmetrically located with respect to the plane of the abutment block, and whose corresponding leg members 37 extend downward and outward at each side of the rail and are provided adjacent the bridge with lugs 38. Each leg 37 is straddled by and housed in a double clamping jaw structure, built up by welding together rolled steel plate members as indicated particularly in Fig. 15. These structures each comprise a pair of transverse, longitudinally spaced clamp jaws 39 secured together in parallel planes by the back piece 40, welded to both and provided with a lengthwise slot 41, and a yoke member 42 externally fitting the spaced jaws at their upper ends and seating on and welded to their top and outer side surfaces, thus further securing and bracing the clamping jaw structure. The construction is duplicated at each side of the rail, the parts being in symmetrical relation to the plane of the abutment plate. The supporting and adjusting bolt 43 passes loosely upward and inward through aligned holes in the yoke member 42 and lug 38, against whose under and upper sides respectively bear the head of the bolt 43 and its nut 44. Each of the jaws 39 is shaped to engage the rail, and preferably at three points of contact therewith marked 45, 46 and 47 respectively and being at the side of the rail head (45), under the rail head (46), and on the edge of the base flange 47, seats 45 and 47

of a given pair of clamp jaws being preferably in a common plane. Final clamping bolts 48, whose heads 49 are countersunk in the inner face of the respective legs 37, near their lower ends at a point below the rail head, extend outward and slightly upward through said legs and through the slot 41 of the adjacent double clamping jaw, and are provided with a nut 51 reacting against the outer face of the backpiece 40. Preliminary adjustment to a moderate clamping is obtained by the bolts and nuts 43, 44, which have an inward and upward cross-drawing effect on the double clamping jaws, the nuts 51 being then backed off sufficiently to permit the outward movement of the lower ends of the double clamping jaws. The final clamping is obtained by screwing the nuts 51 inward on their bolts 48 until the jaws are firmly clamped in place. It will be seen that in this, as in the other forms, adequate clamping is assured. The rail flanges limit the extent of the clamping movement. The legs 37 which are housed by the respective double clamping jaws act to prevent any tendency of the clamp jaws to cramp under car wheel impact. In this form each double clamping jaw has six rail seats coacting with the rail in sets of three each, spaced apart lengthwise of the rail, an arrangement which promotes stability and furnishes a thoroughly adequate means for supporting the block in duly centered position upright on the rail.

I claim:

1. A scotch block having a car wheel abutment seating on the rail tread and upstanding therefrom in the plane of the rail, a pair of lever action clamping jaws adjustably supported from the abutment structure in symmetrical relation to the plane of the abutment and depending below the rail head at each side thereof to receive and grasp the same between them and center the scotch block on the rail and draw it down on the rail head, both jaws extending below the base of the rail and being movable inward against the edge of the adjacent rail base flange to final clamped position, and means to secure the parts therein.

2. A scotch block as set forth in claim 1, in which each clamping jaw is connected to the abutment structure by a lost motion adjustable connection comprising a bolt and nut whose axis extends upward and inward from the jaw.

3. A scotch block structure adapted to straddle and seat on the rail and to slide thereon in upright position under severe car wheel thrust and having a car wheel abutment at its forward end and a rigid downward extension correspondingly located at each side of the rail, a clamp member adjustably suspended from each such extension for movement endwise thereof and adapted to seat against the side and the underside of the rail head, and

means associated with said extension and clamp member for fixing said member in its final seated position.

4. A scotch block of the tie-pusher type adapted for application to rails of different weights and having a car wheel abutment block in the plane of the rail seating on the rail tread and extended rigidly down at each side of the rail into the plane of the ties, and means for holding the car wheel abutment upright on the rail and sustaining it against lateral displacement under car wheel impact comprising loosely mounted clamping jaws at each side of the rail, supported from the abutment block, and means for applying each of said clamping jaws to the adjacent side of the rail in the position of multiple contact therewith regardless of the difference of inclination of the respective planes of double tangency for rails of different weights.

5. A scotch block provided with a car wheel abutment and adapted to seat on the rail tread and having scotch-block-centering and clamping means presenting to the rail six other rail-clamping seats symmetrically arranged with respect to the vertical plane of the rail in sets of three each.

6. A scotch block provided with a car wheel abutment upstanding from the rail and having seven point clamping contact with the rail.

7. A scotch block having a car wheel abutment block in the plane of the rail and seating on the rail tread, and means including two clamping members at opposite sides of the rail movable relatively thereto and adapted to seat against the rail head and rail base flange edge to center the abutment block thereon, and means for holding said clamping members in clamped position.

8. A scotch block of the tie pusher type adjustable to rails of different weights and having an abutment block seating on the rail head and adapted to slide thereon under severe car wheel impact and extended down rigidly at each side of the rail into the plane of the ties, clamp jaws extending down below the base of the rail and movably supported, one at each side of the rail, by the scotch block structure and adapted to seat at each side of the rail head against the rail head and rail base flange edge and beneath a part of the rail, and means for securing said clamp members in seated position.

9. A scotch block adjustable to rails of different weights straddling the rail and having an abutment block seating on the rail head and adapted to slide thereon under severe car wheel impact, a clamping member located at one side of the rail supported by the scotch block structure, movable relatively thereto and adapted to seat against the rail head, rail base flange and the under side of a part of the rail, and means to so seat said movable clamping member.

10. A scotch block adjustable to rails of different weights and having an abutment block seating on the rail head and adapted to slide thereon under severe car wheel impact, movable clamp members extending down below the base of the rail, supported one at each side of the rail by the scotch block structure and adapted to seat against the rail head, rail base flange and the under side of a part of the rail, and means to seat said movable clamp members. 70
11. A scotch block structure adapted to seat on the rail and extend upward therefrom in the plane of the rail and having a car wheel abutment at its front end and, at each side, a downwardly and outwardly extending leg, a rail head clamping jaw supported from each leg, and a pair of angularly related guide slots in each adjacent member and leg, and bolts occupying and co-operating with each set of slots to permit the adjustment and fixing of the clamping jaws in clamped position. 75
12. A scotch block having a car wheel abutment plate adapted to seat on the rail and be maintained in the plane of the rail under severe car wheel thrust, said abutment plate having in a plane transverse thereto a pair of legs welded to the plate and extending downward and outward therefrom, a gusset lug welded to the rear side of each of said legs and to the adjacent side of the plate, a rail clamp member connected to each leg for railward movement with respect thereto, and an adjusting bolt connecting said gusset lug and clamp member. 80
13. A scotch block structure having a car wheel abutment and adapted to seat and slide on the rail in upright position under severe car wheel impact and having at each side a downwardly and outwardly extending leg having therein a slot extending lengthwise thereof, a rail clamping jaw associated with each of said legs and supported from the block, extending below the base of the rail and having therein a slot whose major axis is inclined to the major axis of the slot in the leg and crosses it in an upward and inward direction, a cross bolt occupying said slots for securing the parts in final clamped position, and a supporting and adjusting bolt by which the clamp member is suspended from the block, the axis of said supporting and adjusting bolt extending upward and inward beyond the longitudinal axis of the adjacent leg to cause the bolt to draw the upper end of the clamping jaw inward as well as upward into clamping contact with the rail head. 85
14. A scotch block having a car wheel abutment block adapted to seat on the rail and to be maintained upright in the plane of the rail and having rigid legs extending downward at each side of the rail head, clamping jaws located respectively at opposite sides of the rail and adapted to seat under the rail head, and cross-draw bolts mounted in the respective legs for endwise movement and from each of which the clamping jaw at the other side of the rail is suspended. 90
15. A scotch block having a car wheel abutment plate seating on the rail and upstanding therefrom substantially to the car wheel axle and having secured thereto at opposite sides thereof opposite inwardly facing channels extending downward and outward below the rail base into the plane of the ties, rail clamping jaws at each side of the rail associated with the respective channels and extending under the head of the rail, and means mounted on said channels for moving the clamping jaws into clamped position. 95
16. A scotch block structure having a car wheel abutment plate adapted to seat on the rail and upstanding therefrom in the plane of the rail and having welded to opposite sides thereof a pair of correspondingly located inwardly facing downwardly and outwardly extending channels, rail clamping jaws housed in the respective channels and movable substantially endwise thereof and inward to a bearing on the rail, and means for adjusting and securing said clamping jaws against rails of different weights. 100
17. A scotch block having a car wheel abutment plate seating on the rail and upstanding therefrom substantially to the car wheel axis and having at its front a car wheel abutment and at its rear means to center the abutment plate on the rail, legs near the car wheel abutment extended down rigidly from the abutment plate at each side thereof below the rail base into the plane of the ties, and a clamping jaw at each side of the rail adjustably mounted on one of the legs and extended under the rail head, said legs thereby acting both as tie face abutments and as clamp jaw supports. 105
18. A scotch block structure having a car wheel abutment block adapted to seat on the rail and upstanding therefrom in the plane of the rail and having a pair of opposite inwardly facing channels extending downward and outward from opposite sides of the block into the plane of the ties, rail clamping plate members extending below the rail base, housed in the respective channels and movable substantially endwise thereof and inward toward the rail, and each extending under the rail head, means mounted in the channels for seating said clamping plate members against the head, and means also mounted in the respective channels for adjusting and securing the clamp plate members against the rail base flange of rails of different weights. 110
19. A scotch block having a car wheel abutment block in the plane of the rail and seating on the rail tread, a pair of legs rigidly extending from the block at each side therefrom downward and outward into the plane 115
- 120
- 125
- 130

of the ties, each of said legs having adjustably mounted thereon at a point above the rail head for endwise movement an adjusting bolt extending downward and inward 5 through the leg and abutment block, a clamping jaw suspended from each of said bolts and located at the opposite side of the rail adjacent the other leg, and means carried by each leg below the head of the rail for 10 moving the lower edge of the adjacent clamping jaw inward.

20. A scotch block structure having a car wheel abutment seating on the rail and upstanding therefrom in the plane of the rail 15 and adapted to slide thereon under severe car wheel impact and having a pair of legs extending rigidly downward therefrom on opposite sides of the block, a clamping jaw associated with each of said legs, and having 20 a portion extending inward under the rail head, said jaws extending down below the base of the rail and being movable substantially lengthwise of the legs upward and inward against the rail, a bolt supported in each of said legs, said bolts crossing each other and each extending through the abutment block and hooked into an opening in the clamping jaw on the other side of the block, means for moving each of said bolts 25 endwise to seat the clamp jaws against the rail, and additional means for forcing them inward against the side of the rail.

21. A scotch block having a car wheel abutment adapted to seat and slide on the rail in the plane of the rail and having a pair 30 of legs rigidly supported from the block and extending downward and outward therefrom at each side of the rail into the plane of the ties, a plate-like clamping jaw at each 35 side of the rail associated with the adjacent leg for movement endwise thereof, extending down below the base of the rail and having an inwardly extending portion to seat under the rail head, cross-draw bolts mounted 40 in the respective legs for endwise movement and from each of which the clamping jaw associated with the opposite leg is suspended by its upper end, and clamp screws mounted for adjustment in the respective legs 45 and each abutting on the adjacent plate to seat it against the rail in final clamped position.

22. A scotch block structure having a car wheel abutment seating on the rail and upstanding therefrom in the plane of the rail 50 and having a leg at each side of the block extending downward and outward therefrom, clamping plate members, one at each side of the block, each supported for movement endwise of one of said legs and having seat surfaces adapted to seat on the side and under the head of the rail, a bolt suspending each of said clamping plate members from the leg on the opposite side of 55 the block, means for adjusting the bolts end-

wise, and means for moving the clamping plate to and fixing it in its final seated position.

23. A scotch block of the type adapted to seat on a rail and be maintained upright 70 thereon without drilling the rail having a car wheel abutment plate upstanding in the plane of the rail provided with clamp-supporting rail head straddling legs fast thereto and located in inwardly and upwardly inclined planes meeting in the plane of the car wheel abutment block, and means for applying said clamps to opposite sides of rails of different weights.

24. A scotch block adapted to seat on the rail and having a car wheel abutment adapted to slide on the rail in the plane of the rail under severe car wheel impact, said scotch block having inverted V-shaped structure provided with movable sides and 80 adapted to straddle rails of different weights and extend below the base of the rail, and means for conforming the sides of said structure to the particular rail, each of said sides having an inwardly projecting portion for 85 seating under a part of the rail.

25. A scotch block having an abutment plate adapted to seat on the rail and to slide thereon under severe car wheel impact and having welded thereto at opposite sides 95 thereof near its base a fore and aft brace plate, and having a pair of legs welded to opposite sides of the abutment plate and extending downward and outward below the base of the rail and into the plane of the ties and secured to said brace plate, and bodily movable clamping jaws supported by 100 said scotch block structure and provided with lugs seating under a rail part at each side of the rail.

26. A scotch block structure having a car wheel abutment and adapted to seat on the rail and upstanding therefrom in the plane of the rail and having a fore and aft brace plate at each side of the block, a leg at each 110 side of the block extending rigidly downward and outward therefrom and secured to said plate, a clamping plate associated with each of said legs, said clamping plates having seat surfaces adapted to seat against the side and under the head of a rail, a bolt suspending each of said clamping plate members from one of the legs, means for adjusting each bolt endwise, and means for seating the clamping plate in final position.

27. A scotch block having an abutment plate adapted to seat on the rail and to slide thereon under severe car wheel impact and having welded thereto at opposite sides 125 thereof near its base horizontal brace plates each provided at its rear with means for centering the block, and having a pair of legs welded to opposite sides of said abutment plate and extending downward and outward through an opening in the adjacent brace 130

plate, below the base of the rail and into the plane of the ties, and bodily movable clamping jaws supported by said scotch block structure and provided with lugs seating under a rail part at each side of the rail.

28. A scotch block having a car wheel abutment upstanding from the rail in the plane of the rail and provided with downwardly and outwardly extending legs straddling the rail, a trough-shaped inwardly facing double clamping jaw adjustably suspended from the adjacent leg housing or straddling the same and opposing jaw faces at each side thereof to the side and underside of the rail head, and means adjustably connecting each said double clamping jaw and its supporting leg below the rail head for clamping said jaws in final position.

29. A scotch block according to claim 28 of the tie-pusher type in which the car wheel abutment block is extended rigidly below the rail base into the plane of the ties, and in which the double clamping jaws also extend below the rail base and wherein separate preliminary and final adjusting means are provided for the clamping jaws.

30. A scotch block having a car wheel abutment upstanding from the rail in the plane of the rail and slotted to receive an inverted U-shaped supporting member secured thereto in symmetrical relation to the abutment plate and extending downward and outward therefrom at each side of the rail, a pair of double clamping jaws each built up by welding from plate parts into a trough shape and having at its upper portion a member receiving an adjusting bolt co-operating with the adjacent leg of the supporting U, and a pair of twin clamping jaw members spaced lengthwise of the rail to receive the leg between them, said jaw members extending below the rail base and facing the side and underside of the head of the rail and the rail base flange edge, and means below the rail head seat portions of the jaws for moving the double jaws against the rail for final clamping.

31. In a scotch block, a double clamping jaw fabricated by welding from rolled steel plate pieces a pair of twin jaw members having corresponding seats for the side and underside of the rail head and the rail base flange edge, a spacer piece for the jaw members, and two adjustment-bolt-receiving lugs at the upper end and back respectively of the clamping jaw.

32. A scotch block upstanding above the rail in the plane of the rail and having correspondingly located downward extensions at each side of the rail, a pair of rail clamping jaws, one at each side of the rail, each adjustably supported by one of the downward extensions, preliminary clamping jaw adjusting means, and final clamping jaw adjusting means for each jaw.

33. A scotch block as set forth in claim 32, in which the preliminary adjusting means for a given clamping jaw is mounted on one of said extensions and the final adjusting means for that jaw is mounted on the other.

34. A scotch block having an abutment plate seating on the rail tread and upstanding therefrom in the plane of the rail and having clamping means symmetrically located with reference to the plane of the abutment plate and having at each side of the rail six clamping seats.

35. A scotch block seating on the rail and having a car wheel abutment upstanding above the rail in the plane of the rail, a pair of lever action rail head clamping jaws suspended by their upper and rail head clamping ends from separated points on opposite sides of the abutment structure and depending below the rail head at each side thereof to receive the same between them, independent means for adjusting each jaw separately, the lower ends of said clamping jaws being adapted to be forced toward each other to grip the rail head between themselves and the car wheel abutment, and additional means for securing the parts in their final position.

36. A scotch block seating on the rail and having a car wheel abutment upstanding above the rail in the plane of the rail and having rigid extensions from the car wheel abutment at each side of the rail into the plane of the ties for delivering stress of car wheel impact to the tie and ballast, a pair of lever action clamping jaws suspended from the abutment structure and depending below the rail head at each side thereof to receive the same between them, the lower ends of said clamping jaws being adapted to be forced toward each other to grip the rail head between themselves and the car wheel abutment, and means for securing the parts in their final position.

37. A scotch block having a car wheel abutment block in the plane of the rail and seating on the rail tread, and means for holding it upright on the rail and sustaining it against lateral displacement comprising a clamping jaw at each side of the rail facing the side of the rail head and the rail base, and movably supported from the abutment block, each of said clamping jaws being movable against the adjacent side of the rail head and the rail base into a position of double or multiple bearing contact on the rail, and means for clamping the jaws in that position.

38. A scotch block having a car wheel abutment seating on the rail and upstanding above the rail in the plane of the rail, a pair of opposed lever action clamping jaws each adjustably suspended for movement of translation from abutment structure at one side thereof, each clamping jaw having at its upper end seats for co-action with the adjacent side and

underside of the rail head, depending past the rail head and rail base and having its lower end free for movement toward the lower end of the other clamping jaw into position 5 of final adjustment, and means for fixing the final adjustment.

39. A scotch block seating on the rail and having a car wheel abutment upstanding above the rail in the plane of the rail, a pair 10 of movable clamp jaws mounted on abutment structure and extending below the rail base on opposite sides of the rail and each having seat portions for co-action with the adjacent side and underside of the rail head and with 15 the edge of the rail base, and means for fixing the clamp jaws in clamping position.

40. A scotch block of the type adapted to be applied to the rail without drilling it and mounted on the rail with freedom to slide 20 thereon under excessively severe car wheel impact, having a car wheel abutment upstanding above the rail head to substantially the level of the car wheel axis and having rigid downward extensions below the base 25 of the rail into the plane of the ties at each side of the rail for delivering stress of car wheel impact to the roadbed, and lever action clamp jaws at each side of the rail head for coacting with the underside thereof.

41. A scotch block of the type adapted to be applied to the rail without drilling it having a car wheel abutment supported by the rail in the plane of the rail and extended down rigidly at each side of the rail below 25 the base of the rail into the plane of the ties by means welded to the car wheel abutment at opposite sides thereof, and lever action clamp jaws extending under the rail head above the rail base for coaction with the rail 30 head to clamp the block to the rail and maintain it in upright position.

42. A scotch block having a car wheel abutment plate seating on the rail and upstanding above the rail head in the plane of the rail to substantially the car wheel axis and adapted 45 to slide on the rail under severe car wheel impact, a pair of opposed inwardly facing channels welded to opposite sides of the abutment plate and extending downward and 50 outward therefrom below the rail base into the plane of the ties, rail clamping jaws suspended from scotch block structure at each side of the rail adjacent said channels, and means for adjusting the clamping jaws by 55 movement of translation.

43. A scotch block having a car wheel abutment plate seating on the rail and upstanding above the rail head in the plane of the rail, a pair of opposed inwardly facing channels 60 secured to opposite sides of the abutment plate and extending downward and outward therefrom below the rail base into the plane of the ties, rail head clamping jaws suspended from the scotch block at opposite sides of the rail adjacent said channels and extending be-

low the rail base, said jaws having seats for coaction with the side of the rail head and rail base and the underside of the rail head, means for adjusting them by movement of translation generally lengthwise of the adjacent channel, and screw means associated with each clamping jaw and passing through the back of the adjacent channel for permitting further adjustment and the securing of the clamping jaws in final position. 70

44. A scotch block seating on the rail and having a car wheel abutment upstanding above the rail in the plane of the rail, a pair 80 of clamping jaws having rail head seats at their upper ends and hung by their rail head seat ends from the abutment structure at each side thereof, upwardly and inwardly inclined bolts mounted in scotch block structure and connecting the clamping jaws adjustably thereto for suspending said clamping jaws and for traversing them generally endwise into rail head contact, and transversely extending bolts mounted below the rail head at opposite sides of the rail in scotch block structure and connecting the 85 lower ends of the clamping jaws adjustably thereto for swinging the clamping jaws inward and fixing them in clamping position.

45. A scotch block having a car wheel abutment upstanding from the rail in the plane 90 of the rail to substantially the car wheel axis and provided with downwardly and outwardly extending legs straddling the rail, and a pair of trough-shaped inwardly facing double clamping jaws, each adjustably suspended from the adjacent leg, straddling the same and opposing jaw faces at each side thereof to the side and underside of the rail head. 95

46. A scotch block upstanding above the rail in the plane of the rail and having correspondingly located rigid downward extensions at each side of the rails into the plane of the ties, a pair of rail-clamping jaws, one at each side of the rail, each adjustably supported by one of the downward extensions, preliminary clamping jaw adjusting means, and final clamping jaw adjusting means for each jaw. 105

47. A scotch block having a car wheel abutment plate adapted to seat and slide on the rail in upright position and having rigidly united thereto, at opposite sides thereof, a pair of legs extended downward and outward 110 therefrom below the base of the rail into the plane of the ties to transmit stress of car wheel impact to the tie and ballast and having rear faces in a plane transverse to the abutment plate, a brace plate near the bottom of the abutment plate occupying the angle between the abutment plate and the rear face of the adjacent leg and welded to both, and rail-head-clamping jaws on opposite sides of the rail adjustably supported from said legs. 115

48. A scotch block having a car wheel abut-

ment plate adapted to seat on the rail and be maintained in the plane of the rail while sliding thereon under severe car wheel thrust, said abutment plate having a pair of opposed 5 legs welded to the plate at opposite sides thereof and extending downward and outward therefrom, a supporting lug at each side of the abutment plate welded to a transverse surface of the adjacent leg and downwardly

10 and inwardly inclined toward the abutment plate, and a pair of rail head clamp jaws each suspended from the adjacent supporting lug and movable into clamped relation to the rail head.

15 49. A scotch block having a car wheel abutment upstanding from the rail in the plane of the rail and provided with downwardly and outwardly extending legs straddling the rail, a clamping jaw adjustably suspended

20 from the adjacent leg and having a jaw member located in a plane transverse to the track at one side of said leg and having a slotted back piece welded to the jaw piece and located in a plane at right angles there-

25 to, said jaw extending below the rail base and having seats adapted for co-action with the side and underside of the rail head and the edge of the rail base, and means associated with the adjacent leg and passing through 30 the slot in the back piece for adjusting and securing the clamping jaws in final position.

50. In a scotch block, a clamping jaw fabricated by welding from rolled steel plate pieces and having a clamping jaw member 35 having seats for contact with the side and the under side of the rail head and with the rail base flange edge, a tab piece inclined to the longitudinal axis of the jaw member and welded to the jaw member and a back piece 40 welded to the jaw member, said tab member and back piece having holes for receiving adjustment bolts.

51. A scotch block having a car wheel abutment plate seating on the rail in the plane of 45 the rail and upstanding above the rail head, opposed legs rigidly secured to the abutment plate and extending down at opposite sides of the rail, a pair of clamping jaws each having jaw seats for coaction with the adjacent 50 side and under side of the rail head, and a slotted back piece welded to the adjacent jaw member and located in a plane at right angles thereto, means for adjustably supporting each clamping jaw from abutment structure, 55 and an adjusting bolt associated with the adjacent leg and passing through the slot in the back piece of the corresponding jaw member for adjustment of the jaw toward the rail.

60 52. A scotch block having an abutment plate seating on the rail and upstanding above the rail head substantially to the level of the car wheel axis and provided with 65 downwardly and outwardly extending legs straddling the rail, a lug at each side of the

abutment plate located in a plane extending downwardly and inwardly toward the abutment plate and associated with the adjacent leg, a pair of clamp jaws at opposite sides of the abutment plate having tab portions extending downwardly and inwardly with respect to the longitudinal axis of the clamp members and by which they are respectively suspended from said respective lugs.

53. A scotch block having an abutment 75 plate adapted to be supported on the rail without drilling it and having downwardly and outwardly extending legs straddling the rail, a pair of supporting lugs each welded to the adjacent leg and lying in downwardly and inwardly inclined planes meeting in the abutment plate, and a pair of clamp jaws each having a tab located in a plane inclining downwardly and inwardly to the longitudinal axis of the clamp jaw and suspended by said tab from the adjacent lug by an adjustable bolt extending upwardly and inwardly toward the abutment plate, the structure being symmetrical.

In testimony whereof, I have signed this 90 specification.

STANLEY W. HAYES.
